TUBULAR CONDUCTOR

Franz Unterbusch, Cologne-Mulheim, Germany,
assignor to Felten & Guilleaume Carlswerk
Aktien-Gesellschaft, Cologne-Mulheim, Germany

Application November 4, 1937, Serial No. 172,847
In Germany November 26, 1936

1 Claim. (Cl. 174—130)

It is known to build up the outer tubular conductor of a concentric high frequency cable from a plurality of thin metal bands which are stranded with a long lay. As these bands are easily displaced relatively to one another when the cable is bent, it has already been proposed to form the abutting edges along their whole length in such a way, that a lateral displacement of individual bands is rendered impossible.

10 In order further to improve, simplify and render less expensive the known arrangements, according to the present invention the two longitudinal edges of each band are provided at definite distances with indentations projecting at 15 right-angles to the plane of the band, which indentations may be impressed in a very simple manner, for instance by means of a toothed wheel, and the bands are thus stranded into a closed layer in such a manner that the indentations of the abutting edges of the bands are

staggered relatively to one another so as to render impossible a relative displacement of individual bands.

One example of construction according to the invention is illustrated in the accompanying drawing. The thin metal bands 1 are provided at their edges with indentations 2 which may be bent inwardly as well as outwardly.

What I claim is:

A tubular conductor consisting of a plurality 10 of metal bands each having indentations along its edges at definite distances from one another which indentations project at right-angles to the plane of the band, said metal bands being stranded together with the said projecting indentations 15 of the abutting edges staggered relatively to one another whereby a lateral displacement of the individual bands is prevented.
